[57] **CLAIM**

The ornamental design for a cord clip, as shown and described.

DESCRIPTION

FIG. 1 is a front elevational view of a cord clip showing my new design;

FIG. 2 is an end elevational view thereof;

FIG. 3 is a top plan view thereof;

FIG. 4 is a bottom plan view thereof;

FIG. 5 is a perspective view thereof;

FIG. 6 is a front elevational view of a second embodiment of my new design;

FIG. 7 is an end elevational view thereof;

FIG. 8 is a bottom plan view thereof;

FIG. 9 is a top plan view thereof;

FIG. 10 is a perspective view thereof;

FIG. 11 is a front elevational view of a third embodiment of my new design;

FIG. 12 is an end elevational view thereof;

FIG. 13 is a bottom plan view thereof;

FIG. 14 is a top plan view thereof; and,

FIG. 15 is a perspective view thereof.
